AUTOMATIC VOLUME CONTROL
ARRANGEMENTLoy E. Barton, Collingswood, N. J., assignor to
Radio Corporation of America, a corporation
of Delaware

Application August 15, 1933, Serial No. 685,186

10 Claims. (Cl. 250—20)

My present invention relates to radio receivers, and particularly to automatic volume control arrangements for superheterodyne receivers which do not employ intermediate frequency or radio frequency amplifier stages.

Automatic gain control is usually applied to a radio receiver in present day receiver construction by regulating the bias on a gain control electrode of a radio frequency or intermediate frequency amplifier. There are receiver constructions employed where radio frequency amplifier and intermediate frequency amplifier stages are dispensed with. For example, such constructions are usually employed where compactness and economy of construction are prime considerations. An automobile radio receiver is an illustration of such a compact receiver.

In the case of such compact radio receivers the regulation of the high frequency amplifier bias for gain control is preferably replaced by an automatic control of the signal energy transfer between the signal collecting means and the radio receiver. Of course, to preserve the compactness consideration, it is necessary to utilize this latter type of control without the addition of auxiliary elements which only serve to increase the cost of production and assembly.

Accordingly, it may be stated that it is one of the primary objects of the present invention to provide a radio receiver of the type wherein no high frequency amplification is employed between the signal collecting means and the detector, and wherein automatic volume control is accomplished by regulating the transfer of energy between the signal collecting means and the detector, this regulation being accomplished with a minimum of circuit elements.

Another important object of the present invention is to provide a superheterodyne receiver employing no radio frequency or intermediate frequency amplifiers, and wherein the second detector stage is utilized to control automatically the transfer of signal energy between the signal collecting means and the first detector.

Another object of the invention is to provide a superheterodyne receiver utilizing between the antenna and the audio frequency network solely a combined oscillator detector and a second detector in cascade, the second detector being of the duplex diode triode type and one of the diodes of the second detector being utilized to automatically regulate the transfer of signal energy between the antenna and the combined oscillator detector.

Still other objects of the invention are to improve generally the simplicity and efficiency of

automatic volume control arrangements for superheterodyne receivers, and to especially provide an automatic volume control system which is not only simple and efficient in operation, but economically manufactured and assembled in a compact type of radio receiver.

The novel features which I believe to be characteristic of my invention are set forth in the appended claims, the invention itself, however, as to both its organization and method of operation will best be understood by reference to the following description taken in connection with the drawing in which I have indicated diagrammatically one circuit arrangement whereby my invention may be carried into effect.

In the drawing there is shown a conventional radio receiver of the superheterodyne type between the signal collecting means and the audio frequency network of which solely a frequency changer stage and a second detector stage in cascade are employed. The signal collecting means is illustrated in the drawing by the usual grounded antenna circuit A, this circuit including a resistor R₁ having one side thereof connected to an intermediate point of a coil 1, one side of the coil being grounded. The intermediate tap to this coil divides the coil into two portions L₁ and L₂. The coil portion L₁ is magnetically coupled, as at M₁, to the coil L₃ of the tunable selector circuit 2 of the frequency changer network 3. The coil portions L₂ and L₃ are magnetically coupled. The network 3 is preferably of the combined oscillator detector type well known to those skilled in the art.

Of course, the network 3 can be composed of the equally well known independent first detector and local oscillator circuits, but for the sake of compactness it is preferable to use a combined oscillator detector stage. In that case the circuit 2 is to be considered as the signal frequency input circuit of the oscillator-detector, while the circuit 4 is to be considered as the local oscillation frequency resonant circuit. The numerals 5 and 6 respectively designate the variable tuning condensers in the signal and local oscillation circuits, and a dotted line 7 is shown to represent a mechanical uni-control device, of any well known form, for adjusting the variable condensers 5 and 6.

The circuit 8, in the output of the network 3, is resonant to the operating intermediate frequency and is coupled, as at M₂, to a network 9 also resonant to the intermediate frequency. The specific circuit elements of the network 3 are not shown for the reason that the combined oscil-

- lator detector stage details are not a part of the present invention. However, reference is made to application Serial No. 654,421, filed January 31, 1933 by J. C. Smith for a disclosure of 5 a pentagrid oscillator converter circuit which may be employed in the network 3. The tube employed in such a network is of the type known as a 2A7, those skilled in the art being well aware of its construction.
- 10 The intermediate frequency energy across the circuit 9 is impressed upon a diode rectifier circuit. The diode rectifier circuit functions as the second detector, a tube 10, known as a duplex diode triode, being utilized in the second detector stage. This tube is commercially known 15 as a 55 type tube, and its physical construction has been disclosed in a co-pending application of T. M. Shrader, application Serial No. 622,140 filed July 12, 1932. The tube 10 includes an indirectly heated cathode, the cathode being common for the diode-anode elements 11 and 12, and for the triode grid and plate 13 and 14. The diode elements 11 and 12 are disposed around an 20 extreme portion of the cathode sleeve. The diodes function independently of each other and of the triode section of the tube 10. The electron stream flowing towards the grid 13 and the plate 14 is independent of the electron stream flowing 25 towards the diode anode 11 and the diode anode 12. The high potential side of circuit 9 is connected to the diode anode 11, while the low potential side is connected to the common cathode sleeve lead through a condenser 15, the condenser being shunted by a resistor 16.
- 30 The diode anode 12 is connected by a lead 17 to the ungrounded side of coil 1, and this lead has been designated "A. V. C.". As will be pointed out hereinafter in detail, the lead 17 constitutes the volume regulation path for the receiver.
- 35 Positive potential is applied to the plate 14 of tube 10 from a source B (not shown), the plate 14 being connected to the positive terminal of source B through a path which includes the lead 18 and the audio frequency choke 19. The grid 40 13 of tube 10 is connected by a lead 20 to one side of the resistor 16, through resistor 16a, and it will be understood that there is impressed on the grid 13 the audio frequency component of the rectified intermediate frequency energy, which component flows in the circuit connected 45 to the diode anode 11 and the common cathode lead of tube 10. Resistor 16a attenuates any I. F. voltage across 15 and 16.
- 50 The triode section, including the common cathode, the grid 13 and plate 14, functions as an amplifier of the audio frequency component of the rectified intermediate frequency energy, and this amplified audio energy is transferred to a succeeding audio frequency amplifier 21 55 through an adjustable path which includes the direct current blocking condenser 22 and the manually adjustable resistor 23. The output of the network 21 may then be impressed upon any suitable type of reproducer, such as an electrodynamic loud speaker. It is also possible to impress the output of tube 10 upon the reproducer without further amplification.
- 60 The field coil 24 of the reproducer has one side thereof connected to the negative terminal of the source B, while its other side is grounded. The common cathode sleeve lead of tube 10 is connected to a point on the coil 24 such that the ground side of the coil 24 is at about 25 volts with respect 65 to the point on coil 24 to which the resistor R₂ is

connected. This potential difference is designated by the symbol E₁. A radio frequency by-pass condenser 25 is connected between the grounded side of the field coil 24 and the common cathode sleeve lead of tube 10, the condenser 25 being connected in shunt with the resistor R₂. An audio frequency by-pass condenser 26 is connected between the ungrounded side of condenser 25 and the potential supply source side of choke coil 19.

10 The magnitude of the resistor R₂ is so chosen that the potential difference E₂ in the absence of received signal energy is about 35 volts. Of course, the values for E₂ and E₁ are purely illustrative, and are not given by way of limitation. 15 The potentials E₂ and E₁ function to provide a delay of the automatic volume control action until a predetermined signal intensity level has been attained. In general, the automatic volume control action will not commence until the potential E₂ has become approximately equal to or less than the potential E₁. This type of delayed 20 automatic volume control arrangement has been disclosed by me in connection with a second detector of the 55 type in my copending application 25 Serial No. 640,946, filed November 3, 1932.

With no signal energy impressed on the antenna system A the diode rectifier circuit including the diode anode 11 delivers no rectified energy to the grid 13 of tube 10. In this condition 30 the plate current flow of the triode section of tube 10 is at a maximum with the result that the cathode side of resistor R₂ is at a maximum potential difference with respect to the field coil side of the resistor. The diode anode 12 is connected to ground through the path including lead 17 and coil 1, and therefore with no signal energy being received the diode anode 12 is at a negative potential with respect to the cathode 35 of tube 10. This necessarily follows from the fact that with no signal energy coming in the value E₂ is greater than the value E₁. Since the diode anode 12 is negative with respect to the cathode, this diode circuit is non-conductive.

40 As soon as signal energy is collected by the antenna circuit A, and intermediate frequency energy is impressed upon circuit 9, there is impressed upon the grid 13 rectified energy potential resulting from the potential drop across resistor 16 in the diode detector circuit including diode anode 11. The grid 13 therefore becomes more negative and the plate current flow in the triode section of tube 9 decreases with the result 45 that the value E₂ approaches the value E₁. That is to say, the cathode side of resistor R₂ approaches in potential value the ground side of field coil 24.

50 It will therefore be seen that until the value E₂ actually becomes very close to (about 0.5 volts negative) the value E₁, the diode anode 12 will 55 be sufficiently negative with respect to the cathode of tube 10, to prevent current flow to the diode. As soon as that signal intensity level has been attained which results in E₂ becoming sufficiently low with respect to E₁, the diode circuit 60 which includes the diode anode 12 becomes conductive.

65 This conductivity results in a flow of radio frequency energy through a path which includes the coil portion L₂, the lead 17, the diode anode 70 12, the common cathode of tube 10, the radio frequency by-pass condenser 25, and back to ground to the coil portion L₁. It will be observed that this flow of signal energy is in a direction opposite to the flow of signal energy through the 75

coil portion L_1 . In other words, as soon as the control diode becomes conductive there is induced in the coil L_2 a voltage which is proportional to the voltage across L_1 , minus the voltage across L_2 .

Obviously, as the signal intensity level rises more and more energy is diverted through the coil L_2 , because of a lower effective resistance of the diode circuit, and the relative amount of signal energy reaching the input circuit 2 is reduced. In this way the transfer of energy from the signal collecting means to the frequency changer network 3 is automatically regulated, and in dependence on the variation in amplitude of the received carrier energy, in such a manner that the carrier energy input to the circuit 9 is maintained substantially constant.

The control diode may also be employed as a short circuiting resistance across the antenna coil 1 without the utilization of the afore-described bucking action. This arrangement is obvious, and need not be described in any further detail. It is also possible to apply this general scheme across circuit 2 and other circuits in the receiver for automatic volume control purposes, which may also be so arranged that automatic selectivity may be obtained. It is obvious that the A. V. C. diode may be a separate diode tube in which the cathode is connected to the cathode of tube 10. It is also possible that a separate diode tube may be necessary instead of a common tube to prevent undue signal feedback. The resistance R_1 is large compared to the average antenna impedance, usually about 1000 ohms, so that different antennas cause less variation of signal to L_1 and also to permit poorer regulation of antenna voltage which adds to the effectiveness of the A. V. C. system because the action of L_1 and L_2 is to short circuit the antenna to ground.

While I have indicated and described one system for carrying my invention into effect, it will be apparent to one skilled in the art that my invention is by no means limited to the particular organization shown and described, but that many modifications may be made without departing from the scope of my invention as set forth in the appended claims.

What I claim is:

50 1. In combination, a signal source having parallel paths connected to a common point of invariable potential in signal bucking relation, a tuned circuit coupled to said paths, and means controlled by the signal intensity to cause signal current to flow through one of said paths only when the signal intensity has reached a predetermined level.

60 2. A signal collecting means having parallel paths connected to a common point of invariable potential in signal bucking relation, one of which paths includes an electron discharge device, a tuned circuit coupled to said paths, and a rectifier connected to said tuned circuit, and means connected to said rectifier and said device where- 65 by the latter is rendered conductive only when the collected signal energy intensity attains a predetermined level.

70 3. In a superheterodyne receiver of a compact type including between the antenna circuit and audio frequency network solely a combined oscillator-first detector and a second detector, an automatic volume control arrangement therefor including a pair of parallel paths in the antenna circuit, at least one of which paths is coupled 75 to said oscillator-detector to transfer energy

thereto, and the other path including a control diode, said control diode being connected to said second detector so that the control diode becomes conductive only when received signal energy exceeds a predetermined intensity level, said 5 parallel paths being in signal energy flow opposing relation.

4. In a superheterodyne receiver provided with a first detector and a second detector, the latter including a pair of independent diode sections 10 and a triode section, a tuned circuit coupling the output of the first detector and one of said diode sections, a connection between the grid of said triode section and a point on the circuit of said first diode section, means for connecting the 15 second diode section to an antenna circuit coupled to said first detector input, and means in the space current path of said triode section for maintaining the second diode section inoperative to conduct radio frequency energy until a predetermined intensity level of received signal energy is exceeded.

5. In combination, a signal collector, a pair of parallel paths connected between the collector and a point of invariable potential in signal 25 bucking relation, a tuned circuit coupled to at least one of said paths, a diode rectifier coupled to the tuned circuit, a grid and plate associated with the diode cathode, at least one of said paths being connected to said point through a 30 second diode and an impedance in the space current path between said plate and cathode, and a connection from said grid to said rectifier.

6. In combination, a signal collector, a pair of parallel paths connected between the collector 35 and a point of invariable potential in signal bucking relation, a tuned circuit coupled to at least one of said paths, a diode rectifier coupled to the tuned circuit, a grid and plate associated with the diode cathode, at least one of said paths 40 being connected to said point through a second diode and an impedance in the space current path between said plate and cathode, a connection from said grid to said rectifier, and a source of direct current voltage connected between the 45 said cathode and plate, a second impedance being connected from the negative terminal of the voltage source to said point.

7. In combination, a signal collector, a pair of parallel paths connected between the collector 50 and a point of invariable potential in signal bucking relation, a tuned circuit coupled to at least one of said paths, a diode rectifier coupled to the tuned circuit, a grid and plate associated with the diode cathode, at least one of said paths 55 being connected to said point through a second diode and an impedance in the space current path between said plate and cathode, and a connection from said grid to said rectifier, said cathode functioning as the electron source of the sec- 60 ond diode.

8. In combination, a signal collector, a pair of parallel paths connected between the collector and a point of invariable potential in signal bucking relation, a tuned circuit coupled to at 65 least one of said paths, a diode rectifier coupled to the tuned circuit, a grid and plate associated with the diode cathode, at least one of said paths being connected to said point through a second diode and an impedance in the space current 70 path between said plate and cathode, a connection from said grid to said rectifier, and common tube envelope housing the two diodes, grid and plate.

9. In combination, a signal collector, a pair of parallel paths connected between the collector 75

and a point of invariable potential, a tuned circuit coupled to at least one of said paths, a diode rectifier coupled to the tuned circuit, a grid and plate associated with the diode cathode, at least 5 one of said paths being connected to said point through a second diode and an impedance in the space current path between said plate and cathode, and a connection from said grid to said rectifier, said paths being connected in signal 10 phase opposition, and variations in voltage drop across the said impedance controlling the conductivity of the second diode.

10. In combination with a multiple duty tube including a pair of diode sections and an ampli-

fier section, there being a single cathode common to the three sections, a tuned input circuit coupled between the anode of one diode section and the cathode, a signal collector, a coil having one side thereof connected to the anode of the second diode section, the other side of the coil being connected to the cathode through an impedance, the collector being connected to a point on said coil, said tuned circuit being coupled to said coil, and a connection from a control electrode in said amplifier section to a point in the circuit of said one diode section. 5 10
